UNITED STATES PATENT OFFICE.

CALVIN D. MARSH, OF WILLIAMSPORT, PENNSYLVANIA, ASSIGNOR TO THE ROWLEY & HERMANE COMPANY, OF SAME PLACE.

DOOR OR BLIND CLAMPING MACHINE.

SPECIFICATION forming part of Letters Patent No. 556,684, dated March 17, 1896.

Application filed January 24, 1895. Serial No. 536,119. (No model.)

To all whom it may concern:

Be it known that I, CALVIN D. MARSH, of Williamsport, in the county of Lycoming and State of Pennsylvania, have invented certain new and useful Improvements in Door or Blind Clamping Machines; and I do hereby declare the following to be a full, clear, and exact description of the invention, such as will enable others skilled in the art to which it appertains to make and use the same.

My invention relates to an improvement in door and blind clamping machines, the object being to provide a machine actuated from a suitable source of power and designed to clamp doors and blinds, hold the same under compression until wedged, and then instantly release the article, the clamps being adjustable so as to operate on articles of various sizes.

My invention consists in the parts and combinations of parts as will be more fully described and pointed out in the claims.

In the accompanying drawings, Figure 1 is a sectional view. Fig. 2 is a plan view. Fig. 3 is a view in end elevation. Figs. 4 and 5 are enlarged detail views.

A represents a frame composed of end and side sections, and provided in its upper face with two clamping-plates B B' extending lengthwise the machine, each clamping-plate being provided with a series of dogs C adapted to engage the side rails of a door or window-blind. The clamping section or plate B is rigidly secured to the upper face of the machine, near one side thereof, while the other section or plate B' is secured near its ends to the blocks C' C', which latter are mounted on screws D carried by the slides E. The slides E are in contact with the inner faces of the end sections of the machine and rest on and are supported by the lugs a, which latter project inwardly from said end sections and are provided at their ends with the inwardly-turned tips or flanges c, which latter form bearings for the screws D.

The two screws by which the adjustable clamping-plate is moved toward or away from the other clamping-plate can, if desired, be coupled up so as to move in unison; but in

the present instance I have provided each 50 screw with a hand-wheel c' c' for turning each independently of the other.

From the foregoing it will be seen that one of the clamping-plates is rigidly secured to the machine-frame, while the other is connected near its ends to slides mounted on lugs or bearings projecting inwardly from the ends of the frames. These slides with the clamping-plate thereon are reciprocated through the instrumentality of the following parts: 60

H is a shaft carrying a belt-wheel H' and the two friction-cones H². These cones are placed apex to apex, a space being left between them for the shifting devices which operate to shift the cones, as will be more fully 65 described later on. These cones are splined to the shaft so as to revolve therewith, but are free to slide thereon so as to bring either cone in frictional contact with the friction-wheel H³. The cones H² are each composed of paper 70 bodies h with metallic ends h', while the wheel H³ is composed wholly of metal. The wheel H³ is located in a plane between cones H² and when centrally between them is not engaged by either. When the cones H² are, however, 75 shifted in either direction, one cone H² is moved into contact with wheel H³, thus causing the latter to revolve in one direction, and when shifted in the opposite direction, so as to bring the other cone H² into contact with 80 wheel H³, the latter is rotated in the opposite direction.

The wheel H³ is secured to shaft H⁴, which latter is mounted in bearings H⁵ and provided with a pinion H⁶. This pinion H⁶ engages 85 the teeth of pinion H⁷ secured to crank-shaft I. Shaft I is mounted in bearings in the ends of the frame, and is also supported between its ends in bearing I', and is provided near its ends with cranks I², which latter are connected by pitmen I³ with the slides E. This crank-shaft makes simply one-half a revolution and in this movement throws the movable clamping-plate B' from one extreme to 90 the other. In Fig. 1 the clamping-plate is at 95 its inner throw or in its position while clamping, and to release the door or blind held therein the crank would have to move over

to its other extreme. The movement of the clamp B' is uniform for all sizes of work, and the adjustments for the various sizes is, as before stated, accomplished by the screws D.

5 J is a Y-shaped lever, one arm, J⁴, of which is preferably bifurcated at its lower end to engage the collar J' connecting the double cones II², while the other arms, J³, are each provided with a set-screw J². The arms J³ rest under one of the cranks, and the two set-screws are adapted to engage the crank and be moved thereby sufficiently to move the sleeve J' lengthwise a sufficient distance to separate the friction-wheels and instantly release the crank-shaft.

10 Connected to the sleeve J' is the shifting-lever K, which latter is connected, through levers K' and K², with the double treadle K³. Now by bearing down on one end of the treadle the cones II² are moved lengthwise, the shaft thus bringing one of the cones in contact with the friction-wheel II³. Now for the purposes of illustration I will suppose that the parts are in position shown in Fig. 1.

15 at the start or the clamps are closed. The engagement of the frictional wheels will operate the crank-shaft through the gearing heretofore described and turn the crank in the direction of the arrow or to the right. As

20 the crank approaches its extreme throw, as it completes a half-revolution, it engages the set-screw in the right-hand arm J³, rocks said arm slightly, and shifts the sleeve carrying the cones II² sufficiently to disengage the friction-wheels. The movable clamping-plate would then be in open position or in a position to receive a door or blind and the crank would be in position slightly below a horizontal plane, thus locking it against movement until returned by the friction-wheels.

25 After a door or blind has been placed on the dogs the treadle is actuated to throw the other friction-cone into contact with the friction-wheel, thus reversing the motion of the crank-shaft and bringing it back by a return movement to the position shown in Fig. 1. As the crank nears its position, as shown in Fig. 1, it strikes the set-screw in left-hand arm J³ and shifts the cones, as before described, thus

30 releasing the friction-wheel and withdrawing the power from the crank-shaft. The outer end of the latter has, however, by this time passed below the horizontal center of the shaft, thus locking the crank, pitmen and

35 clamping-plate, and holding the work firmly pressed or clamped together. The parts constituting the door or blind are thus wedged or pinned, as desired, after which it is released and another inserted. By means of

40 the double treadle and cones the direction of rotation of the crank-shaft can be instantly changed, and by means of the screws the machine can be adjusted for doors or blinds of any size within the limits of the machine.

45 The greatest pressure is applied when the joints are nearly closed, and the parts are

held under this pressure until wedged. By moving the treadle which actuates the friction-gear the article is released.

It is evident that numerous slight changes might be resorted to in the relative arrangement of parts herein shown and described without departing from the spirit and scope of my invention. Hence I would have it understood that I do not restrict myself to the exact construction of parts herein shown; but,

Having fully described my invention, what I claim as new, and desire to secure by Letters Patent, is—

1. The combination with a frame, and movable clamping-plate, of a rocking crank-shaft, pitmen extending from the cranks for moving the movable clamping-plate, and mechanism engaged and operated by the crank-shaft in each of its extreme movements for stopping the movement of the movable clamping-plate, substantially as set forth.

2. The combination with a frame, a movable clamping-plate, a crank-shaft, and pitmen extending from the cranks to slide the movable clamping-plate, of gearing, a lever for connecting and disconnecting the gearing, said lever operated by the engagement therewith of the crank-shaft to automatically disconnect the gearing, and a double treadle connected with said lever to swing it in either direction, substantially as set forth.

3. The combination with a frame, a movable clamping-plate, a pitman, and a crank-shaft, of gearing, a pivoted lever having a pair of arms either of which is adapted to be struck by the crank-shaft to shift and disconnect the gearing, and means for connecting the gearing, substantially as set forth.

4. The combination with a movable clamping-plate, a crank-shaft and pitmen connecting the plate and cranks, of means for actuating the crank-shaft and means engaged by the crank as the latter passes below a horizontal plane for stopping the clamping-plate, substantially as set forth.

5. The combination with a movable clamping-plate, a crank-shaft and pitmen connecting the plate and cranks, of means for actuating the crank-shaft in either direction, means engaged by one of said cranks as the latter approaches the end of its throw, for stopping the clamping-plate, and devices for reversing the direction of movement of the shaft.

6. The combination with a stationary clamping-plate, a crank-shaft and pitmen connecting the crank-shaft and movable clamping-plate, of a driving-shaft, friction-cones thereon a friction-wheel secured to a driven shaft and adapted to be engaged by the cones, means operated by the crank-shaft for shifting the cones whereby either cone can be moved into contact with the friction-wheel, and devices connecting the driven shaft and movable clamping-plate.

7. The combination with clamping-plates,

a rock-shaft and pitman connected with one of said clamping-plates and adapted to reciprocate it in opposite directions, of reversing-gearing connected with said rock-shaft and a reversing-treadle whereby power may be transmitted to the rock-shaft to turn it in either direction and to open or close the clamping-plates, substantially as set forth.

In testimony whereof I have signed this specification in the presence of two subscribing witnesses.

CALVIN D. MARSH.
